UNITED STATES PATENT OFFICE

CHARLES S. CRICKMER, OF DALLAS, TEXAS, ASSIGNOR TO THE GUIBERSON CORPORATION, OF DALLAS, TEXAS, A CORPORATION OF DELAWARE

DRILL BIT

Application filed May 24, 1928. Serial No. 280,142.

This invention relates to a drill bit and particularly to improvements in the construction of the stock thereof and the means for supporting the disk cutter and gauge rollers in operative relation, as generally disclosed in the patent to I. C. Bell, No. 1,657,611, dated January 31, 1928.

In this patent if the holding nuts for the cheek plate and gauge roller at one side of the bit stock be removed for repair or replacement of worn parts, the plate at the opposite side of the bit is released and a new adjustment thereof must be effected when the parts are reassembled. Further the gauge roller is journaled upon a pin inserted from the top of the cheek plate when removed from the stock and it is difficult to insure an accurate length of this pin so that it will firmly bear at each end upon the holding nuts which prevent axial play particularly when the length of the reaming teeth upon the roller is materially increased relative to the gauge face thereof.

The present invention avoids these objections by removably attaching the supporting bolt for the cheek plates to the bit stock so that either plate may be removed independent of the other, and also provides means for adjusting the length of the pivot pin of the gauge roller so as to insure proper contact with the holding nut therefor mounted upon the supporting bolt. It also provides protected means for locking this nut against displacement and otherwise perfects the structure of the stock and its water passages to secure the most efficient results under continued deep well operation.

The invention has for an object to provide a novel and improved construction for mounting the cheek plates carrying the gauge rollers upon the stock of the bit so that the plate at either side of the stock may be removed without releasing the opposite plate.

Another object of the invention is to present a new structure of gauge roller pin or shaft having adjusting nuts at its opposite ends to engage the holding nuts of the cross bolts by which the shaft is retained against axial play, together with a material elonga-

tion of the reaming teeth upon the roller relative to the gauge face thereof.

A further object of the invention is to provide a novel arrangement of the water passages through the stock and depending 55 tongue therefrom to insure a full and free delivery of liquid upon the disk cutters.

A construction designed to carry out the invention will be hereinafter described, together with other features of the invention. 60

The invention will be more readily understood from a reading of the following specification and by reference to the accompanying drawings, in which an example of the invention is shown, and wherein:

Fig. 1 is an elevation, with parts in section,

Fig. 2 is an elevation at right angles to Fig. 1,

Fig. 3 is an elevation of the bit stock,

Fig. 4 is a similar view at right angles 70 thereto,

Fig. 5 is a horizontal cross-sectional view taken on the line 5—5 of Fig. 3,

Fig. 6 is an underside view, and

Fig. 7 is an enlarged horizontal cross-sectional view taken on the line 7—7 of Fig. 1.

Like numerals refer to like parts in the several figures of the drawings.

The numeral 10 designates the body of the bit having a threaded pin 11 at its upper 80 end and an angular stock 12 depending therefrom which terminates in a tongue 13. The opposite faces of the stock are formed with seats 14 to receive the flanges 15 of the cheek plates 16 which have a reduced lower end 17 provided with a bearing for the laterally offset axles 18 upon which the circular cutting disks 19 are journaled. These axles when in parallel relation have a bearing 20 in the tongue 13 wherein they are held against 90 rotation, while the lower wall of the stock is merged on a curved line into its tongue to produce an arched clearance space 40 above the cutters 19.

The cheek plates are formed with a recess 95 21 to receive the reamer and gauge roller 22 which has its pin or shaft 23 seated in the plate and retained against both rotary and axial movement by the cone or holding nuts 100 24 upon the cross bolts 25 mounted in aper-

tures in the stock 12. To permit release and removal of either cheek plate without releasing the opposite plate, these bolts are secured to the stock by nuts 26 threaded thereon and seated in recesses 27 at the opposite faces of the stock. The cone nuts when in holding position are within the outer face of the plates and are retained by a suitable locking device, such as the pin 28 extending through the nut and resting in the groove 29 upon the face of the plate. These holding nuts perform the dual function of retaining the cheek plates in position and also holding the pins upon which the gauge rollers are journaled.

15 To prevent axial play due to slight differences in the length of the pin 23, the ends thereof are provided with set screws 30 which may be adjusted to secure accurate contact with the holding nuts 24, so that the pin is held against both rotative and axial movement. It is also found desirable to increase the length of the operative face or teeth 31 of the reamer relative to the gauge face 32 thereof, and these teeth are therefore formed 20 of greater length than the gauge face which provides an effective side balance for the stock and cutter disks to prevent the latter being thrown out of a vertical plane.

30 The head 10 of the bit is formed with any suitable water passage and in Figs. 3 and 4 the stock has a longitudinal water passage 33 which is intersected at its base by a transverse bore 34 closed at its outer end by a plug 35 which permits access for cleaning the passages. From this transverse bore parallel 35 passages 36 extend longitudinally of the stock at each side of its axial center and are enlarged at their discharge ends 37 to provide a proper flow of liquid at the disk cutters. 40 These enlarged ends are interiorly threaded at 38 to receive a wear sleeve 39 which may be replaced when worn. The disposition of the bores forming the water passages renders the production of the bit more economical 45 and avoids mechanical difficulties in the drilling of the usual diagonally arranged passages through the thinner material of the stock and tongue, such as are shown in Figs. 1 and 2.

50 The operation of the invention will be apparent from the foregoing description and it will be seen that the invention relates to improvements in the several elements of the drill bit developed in the practical manufacture thereof and effecting the improved 55 functions as before explained.

While the specific construction of the several parts has been shown and described the invention is not confined thereto as changes and alteration may be made therein without departing from the spirit of the invention as recited in the following claims.

What I claim, is:

1. In a drill bit, a stock having seats at its 65 sides and an extended tongue, vertical sup-

ports disposed in said seats, bolts retained in the stock against axial movement, means adjustable upon said bolts to clamp said supports in said seats, and rolling cutters journaled between the supports and tongue. 70

2. In a drill bit, a stock having seats at its sides and an extended tongue, vertical supports disposed in said seats, bolts retained in the stock against axial movement means adjustable upon said bolts to clamp said supports in said seats, rolling cutters journaled between the supports and tongue, and means at the outer face of said supports for preventing rotation of the clamping means upon said bolts. 75

3. In a drill bit, a stock having seats at its sides and an extended tongue, vertical supports disposed in said seats, bolts retained in the stock against axial movement and having means to clamp said supports in said seats, rolling cutters journaled between the supports and tongue, shafts for said rollers alined with the clamping means, and means upon said shafts for adjustably contacting with said clamping means. 80

4. In a drill bit, an apertured stock having longitudinal seats at its sides and a depending tongue, cheek plates having flanges disposed in said seats, cross bolts extended through the apertures of the stock and carrying retaining means engaging the opposite faces thereof, holding nuts threaded upon the opposite ends of the bolts to clamp the cheek plates to the stock, and rolling cutters journaled intermediate the cheek plates and tongue. 85

5. In a drill bit, the combination of a bit stock, cheek plates fitted against the stock, a threaded fastening bolt passing through the stock, nuts upon said bolt engaging the opposite faces of the stock, means adjustable upon said bolt for clamping said plates in contact with the stock, and roller cutters journaled at the lower ends of said plates. 90

6. In a drill bit, the combination of a bit stock, a tongue depending from the stock, cheek plates fitted against the stock, a pair of fastening devices passing transversely through the stock, one of said fastening devices passing through the plates near their top and the other fastening device passing through the plates just above the tongue, and rolling cutters journaled between the lower ends of the plates and the tongue. 105

7. In a drill bit, the combination of a bit stock, a central tongue depending from the stock, the stock having vertical seats on each side and shoulders overhanging the seats, cheek plates having flanges engaging in said seats on each side of the stock and abutting the shoulders, an upper fastening bolt passing through the tops of the plates and the stock just under the shoulders, bottom fastening bolts passing through the plates and the stock just over the tongue, and cutter disks jour- 110

130

naled between the tongue and the cheek plates.

8. In a drill bit, the combination of a bit stock, a tongue depending from the stock, 6 cheek plates fitted against the stock and hanging on each side of the tongue, a pair of fastening devices passing transversely through the stock and the cheek plates at the top and bottom of said stock, axles mounted on opposite 10 sides of the tongue and supported by said tongue and the depending ends of the cheek plates, said axles being mounted in parallel and offset relation and held in the tongue against rotation, and disk cutters journaled 15 on said axles.

In testimony whereof I affix my signature.
CHARLES S. CRICKMER.
